ASH TRAY

John H. Dawson, 359 Congressional Lane, Rockville, Md.,
assignor of fifty percent to John H. Dawson, Jr., Rock-
ville, Md.

Filed May 29, 1963, Ser. No. 75,110

Term of patent 14 years

(Cl. D85—2)

FIG. 1.

FIG. 2.

FIGURE 1 is a perspective view of an ash tray embodying my new design; and

FIGURE 2 is a side elevational view thereof.

The sides not shown are substantially the same in appearance as the sides shown. The golf ball representation is permanently attached to the ash tray.

The dominant features of my design reside in the portion shown in full lines.

I claim:

The ornamental design for an ash tray, substantially as shown and described.
